FUEL PUMP

Walter A. Wood, Detroit, Mich.

Application January 2, 1941, Serial No. 372,704

2 Claims. (Cl. 103—44)

The present invention relates to pumps particularly designed to move fluid fuel for automotive internal combustion engines, from the storage tank of the vehicle to the carburetor or charge forming device.

In the conventional vehicle it is customary to locate the fuel tank at the rear and at a somewhat lower level than the carburetor. Further, in order to enable the latter to function properly, it must be equipped with a constant level device such as a float bowl in which a float controls the inflow of liquid fuel. But, because of the usually small capacity of such float bowls, the valve operated by the float is incapable of withstanding very high pressures.

The problems, therefore, confronting the designer of fuel pumps include that of elevating the fluid fuel variable distances, due to the departure of the vehicle from a truly horizontal position, the delivery of such fuel to the carburetor under a pressure less than that required to force open the float controlled valve, and the meeting of the variable demands for fuel by the engine under changing load conditions.

Among the objects of the present invention is to overcome the objections to many of the forms of pumps intended to solve the above problems and provide a structure which will deliver a sufficient quantity of fuel under all conditions at such a pressure as will permit an easy, even flow into the carburetor without danger of flooding.

Other objects will readily appear to those skilled in the art upon reference to the following description and accompanying drawing in which

Figure 1 is a longitudinal vertical section through a preferred form of the pump.

Figure 2 is a similar view of a slightly different form of pump and also showing the pneumatic operating means.

Figure 3 is a section through the diaphragm portion of another form of the pump.

Referring particularly to Figure 1, the pump is indicated as comprising a body member 20, provided at one end with an inlet conduit 21, the outer end of which is threaded to enable the connection of suitable tubing (not shown) leading from a fuel tank (also not shown). The inner or other end of conduit 21 opens through a boss 22 to the under face of body 20, the boss projecting substantially centrally of a seat 23 upon which is secured, with the interposition of a gasket 24, a settling chamber 25.

Surrounding the boss 22 and covering the

chamber 25 is a screen element 26, this being dished as shown to permit the projection into the upper part of the chamber to some distance, of an outlet tube 27 to thereby form a gas or air filled pulsation cushioning chamber above the liquid in the settling chamber.

The outlet tube 27 from chamber 25 is a part of the inlet conduit 30 for the pump proper and forms a seat for pump inlet valve 31 opening against a spring 32 acting against and guided by a plug 33.

Conduit 30 leads to a pump chamber 35 formed in the pump body 20, and shown as a concavity on the underside of the body, and over which is secured a flexible diaphragm 36 which, in turn, is covered by a reversely concave cover plate 37 having a substantially centrally located boss 38 into which is secured a tube 39 communicating with a pulsating means such as is shown in Figure 2. Cover plate 37 is also provided with a lateral boss 37a into which is secured a plug 37b having a capillary passage 37c, the purpose of which will be described later. Leading from chamber 35 is a short tube 45 forming a part of outlet valve 47 which is substantially the same as valve 31.

Conduit 46 and its continuations lead to the point of discharge (usually a carburetor) and in order to properly regulate such discharge, it is preferred to insert in this conduit a pulsation dampener and also a pressure regulator.

The dampener is indicated at 50 and shown as a small chambered element opening downwardly into conduit 46, while a suitable form of pressure regulator is shown to the right thereof in this figure. This form of regulator consists of a short tubular continuation 51 of conduit 46 having a cross tube 52, closed at one end 53 and flared at the other to produce a fairly large dished flange 54 over which is secured a flexible diaphragm 55 pressed toward conduit 51 by a spring 56 mounted in a suitable cap 57 provided with a small opening 58. The diaphragm 55 carries a plug member 60 lying in the cross tube 52 and loosely fitting therein and provided with a circumferential groove 61 arranged to be in line normally with the bore of tube 51. When back pressure develops in the delivery conduit, fluid passes along the plug body to the underside of diaphragm 55 and lifts the latter and, of course, the plug 60, thereby partially or entirely cutting off flow through the conduit, by virtue of the groove 61 being moved out of registry with the passage or bore.

Referring now to Figure 2, this shows a pump

involving substantially the same elements as that of Figure 1, excepting the back pressure regulator. In this figure, the settling chamber and its associated screen, inlet valve, etc., is the same in form and function as that already described and will be designated as a whole as 25. The same similarity of construction exists in the pump chamber 35, outlet valve 45-47, outlet passage 46 and chamber element 50.

The pump body, however, contains a second chamber 15, for convenience located in alignment with pump chamber 35 and of lenticular shape. This chamber 15 is divided by a diaphragm, conveniently an extension of the pump diaphragm, and the upper portion communicates through a passage 77 with outlet passage 46.

Coating with the underside of diaphragm 76 is a valve member 78 which is cylindrical and is provided with an annular groove normally registering, or substantially so, with the passage 39a, to one end of which is connected a tube 39 leading to the pulsator and the other end of which is connected to the pump chamber 35.

Valve member 78, as implied, extends across passage 39a and into a tubular boss 79, in which, or a tubular extension thereof 80, it is supported and held against the diaphragm 76 by a suitable spring 81. The valve member 78 preferably fits snugly in its tubular guide so as to effectively valve the passage 39a and, in order to permit free movement, it is necessary to provide for balancing the pressure in the small chamber or space under diaphragm 76 and in the tube 80. This may be accomplished by providing a passageway 78a connecting the two spaces, either through the member 78 as shown or through the pump body.

This valve member 78 and its associated operating parts serve also as a back pressure regulator in that pressure developing in passage 46 causes depression of diaphragm 76 and thereby moves valve member 78 downwardly so as to throttle or substantially entirely cut off passage of pulsations through passage 39a to the pump chamber.

Also set into a wall of passage 39a is a plug 37c similar to the plug 37c in Figure 1 and for the same purpose. In this form of pump as well as in the others shown, including Figure 1, already described, pulsations of alternating increase and decrease of pressure are produced in passages 39, 39a and corresponding passages, through their being connected through a suitable tube 39b to a pneumatic pulsator such as is shown in Figure 2.

This device comprises a cylinder 85, flanged as at 86 for attachment to the wall 87 of an engine crankcase adjacent to the camshaft 88. The tube 39b is secured as by a suitable nipple 89 to the closed end of cylinder 85 while the latter is occupied by a piston 90 actuated in its inward movement by a suitable cam 91 on the camshaft 88. The outward return of the piston 90 is accomplished by means of a spring 92 acting between flange 86 and a suitable flange or cover plate or both 93 on the projecting end of piston 90.

While the relative proportions of the cylinder 85, tube 39b (bore and length) are not critical, it is necessary that they be such that the piston substantially completely displaces the air from the cylinder 85 into the tube 39b and pump to produce a quite high pressure therein and, conversely, when the piston moves outward to permit a quick drop to sub-atmospheric pressure.

Further, the tube 39b may be sufficiently long to enable the pump to be located away from the engine to avoid undue heating, and of sufficiently large bore to avoid undue internal friction, not, however, so large as to materially reduce the pressure transmitted to the pump diaphragm. Satisfactory results have been obtained with a pump capacity of twenty gallons per hour at 2000 R. P. M. engine, speed in using a pulsating cylinder of 1½ inches bore and $\frac{1}{8}$ inch stroke and a tube (39b) of 12 inches in length and with a bore of .112 inch. These dimensions are of course variable to some degree as will be readily recognized.

Tests seem to show that the pressures in the pulsating elements should be substantially maintained, so that if a longer tube 39b is necessary, or desirable, it should be somewhat smaller, though not so small that the higher wall friction interferes with the rapid passage of air.

In the form of pump shown in Fig. 3, a somewhat different form of pulsator is used. In this form, the fuel pumping diaphragm is indicated at 135 with the pump chamber at 136, all of the fuel passages, valves, etc. being in the upper part 137 of the structure and not being shown. Below the diaphragm 135 is a dished plate 140 having in its center an opening 141 allowing communication between the space below the diaphragm and a pulsating chamber 145, in the bottom of which is a second diaphragm 146 fixed at its center to an actuating rod 147 and constrained against flexure, except at or near the edges, by metal plates 148 and 149. Both diaphragms 135 and 146 are sealed at their edges by the flanges 150, screws 151, and the edge of the intermediate plate 140.

The upper end of the rod 147 is guided in a suitable spider or perforated plate 152 which also serves as an abutment for a spring 153 acting against a flange 154 and tending to thrust the rod 147 downwardly. A small opening 155 serves to vent the chamber under the diaphragm 146.

In the edge of plate 140 which is sufficiently thick for the purpose is a small passageway 160 enlarged in its outer portion to receive a threaded plug 161 also provided with a passage which may be formed by providing the threaded shank with a flat side and notching the underside of the head, as indicated at 162. This passageway opens to the outside air from chamber 145 and corresponds to passage 37c in Figs. 1 and 2. By making the notch 162 suitably small and the flat side of the screw shank of suitable proportionate size, the passage so produced may be regulated in size from that provided by the notch when the screw is tight.

Mention has been made above of the capillary passage 37c opening from the atmosphere into the air passages of the pumps shown in Figures 1 and 2. The term "capillary" as applied to the passage 37c is intended to mean only that it is of quite small diameter but not of microscopic dimensions, since it is necessary that air may pass but only very slowly. Such a small continuously open passage is a very important element of the pump construction and has several important functions.

In one of its functions, this passage acts as a pressure stabilizer or air volume regulator in that it admits air when the average pressure within is below atmospheric and allows escape of air when the average pressure is higher than atmospheric. The capillary dimensions of the passage, however, prevents free passage of air

because of the high wall friction and, therefore, the action of the rapid fluctuation of pressure due to the movement of piston 98 or diaphragm 146 upon the pump diaphragm is not materially affected.

A second function of the passage 31c, more or less incidental to the first, is that of ventilation so that no condensation can take place within the air passages.

A third function, applicable particularly to 10 the pump of Figure 2, is that of bleeding the pressure from passage 39a when the valve 18 has closed.

The present case is in part a continuation of my previously filed application Serial No. 53,528, 15 filed December 9, 1935, on Fuel pumps, and issuing as Letters Patent No. 2,228,292, on January 14, 1941.

I claim:

1. In a fuel pump for internal combustion engines, a pumping diaphragm, an air chamber of 20

which said diaphragm forms a wall, a second movable wall for said chamber, means for moving said second wall to thereby compress and decompress air in said chamber, and means for 5 permitting air to pass in or out of said chamber, said means including a continually open capillary passage extending laterally from the outside air to the air chamber between the said movable walls.

2. In a fuel pump for internal combustion engines, a pumping diaphragm, an air chamber of which said diaphragm forms a wall, a second movable wall for said chamber, means for moving said second wall to thereby compress and decompress air in said chamber, means for permitting air to pass in or out of said chamber, said means including a continually open capillary passage, and means for adjusting the size of said passage.
